BAG OPENING PROCESS AND MACHINE, INCLUDING MOBILE BAG OPENING ARMS

Harvey A. Edmonds, Chicago, Ill., assignor to
Swift & Company, Chicago, Ill., a corporation
of Illinois

Application November 1, 1949, Serial No. 124,807

12 Claims. (Cl. 226—59)

1

The present invention relates to an automatic machine for opening folded bags formed of paper or the like and for positioning the open bags so that they may be readily filled either by hand or by additional automatic machinery.

In many fields, particularly the food industries, it is highly desirable from the standpoint of sanitation to handle the food products by machinery until the packaging is fully complete. Such procedure also is desirable from the standpoints of economy and speed of production.

It is readily apparent that one of the easiest methods of packaging either single units of goods in bulk is to insert the goods into a preformed sack-like container. The major problem that has confronted persons seeking to adopt this method of packaging for automatic operation is that of picking up the sack from a stack, opening it, and holding it open in proper position for filling.

The present invention has for its principal object the solving of this problem. A machine utilizing my invention not only can pick up a bag of paper or similar material from the top of the stack, open the bag and position it for filling by hand or by machine, but, in addition, it is adapted to hold the bag open and fixed in that position for a sufficient length of time for the filling operation to have taken place. Furthermore, the machine allows a relatively clear path for access to the interior of the bag for the insertion of the material to be packaged. The invention may be adapted for the filling of bags in either the vertical or horizontal position.

Additional objects and advantages will become apparent from the following description taken in conjunction with the drawings, in which:

Figure 1 is an elevational view of an embodiment of the invention in which bags are to be filled while in the inverted position with parts of the machine broken away to better illustrate the invention.

Figure 2 is an enlarged view of the bag-opening arms.

Figure 3 is an elevational view of the part of the machine for removing the folded bags from a stack thereof.

Figure 4 is a section taken at line 4—4 of Figure 1.

Figure 5 is a second embodiment in which the bag is held for filling in a horizontal position, and

Figure 6 is an embodiment in which the bag is held for filling while in the vertical position with the opening at the top.

2

In brief, the invention includes a finger feed mechanism, generally 15, which is adapted to be moved from a first position at which a bag has been inserted between the fingers to a second position at which a bag-opening arm mechanism, generally 16, opens the bag and holds it in a suitable position for the bag to be filled. The invention may be used with other apparatus for filling the bags and for moving and sealing them after they have been filled. While such apparatus has not been illustrated, it will be apparent from the subsequent description that such equipment can be coordinated with the present invention with ease. Of course, should it be desirable to do so, such additional steps can be performed by hand.

Finger feed

The finger mechanism 15 for gripping the bag includes one or more pairs of individual fingers 17 pivotally mounted with respect to a carrier, in the specific embodiment a supporting arm 18, by means of shafts 19. Intermeshed gear segments 20 are adapted to be moved simultaneously with individual fingers 17 to cause the fingers to move in unison. The mounting of the fingers 17 and gear segments 20 may be such that they are each attached to shafts 19 with the shafts journaled in supporting arm 18, or the fingers 17 may be affixed to respective gear segments 20 and the finger and gear segment journaled on shaft 19. In the present instance, the gear segments 20 and fingers 17 are each fixed to the shaft 19 and the shaft journaled in the supporting arm 18. Finger tips 21 are mounted so as not to come tightly together as the fingers 15 close over a bag. The finger tips 21 function to guide the mouth of the bag in the proper direction.

A lever 22 also is attached to one of shafts 19 and positioned so that the lever will be moved back and forth across the longitudinal center line of supporting arm 18 as fingers 15 are opened or closed. A pin 23 is affixed to supporting arm 18, and a pin 24 is affixed to lever 22 with tension spring 25 interconnecting pins 23 and 24. Inasmuch as the spring will be extended each time lever 22 rotates across the longitudinal centerline of supporting arm 18, the spring insures that the fingers 17 will remain open or closed until a suitable force is applied to pivot lever 22, which pivotal movement is transmitted to the other of the pair of fingers through gear segments 20.

A pair of pins 26 is attached to each of individual fingers 17 in such a position that as the fingers come together the bag will be tightly squeezed between the two pins and prevent any air from

passing into the interior of the bag. The function and action of pins 26 will be described hereinafter in greater detail.

Supporting arm 18 is pivotally mounted by shaft 27, and the pivotal movement is controlled from shaft 28 by means of a crank 29 thereon and a connecting rod 30 between crank 29 and supporting arm 18. Suitable means, including a motor 31, are incorporated to cause rotation of shaft 28.

Before the supporting arm 18 is rotated downwardly, the fingers 17 will have been closed on a bag and lever 22 will be pivoted forwardly (to the left in Fig. 1) of the longitudinal center line of supporting arm 18, as shown in the second from the bottom of the alternate positions of arm 18 in Fig. 1. As arm 18 approaches its lower terminus, the lever 22 comes into contact with an adjustable stop 33 to pivot the lever 22 backwardly across the longitudinal center line of supporting arm 18 sufficiently to enable spring 25 to open the fingers. The point at which this action takes place may be varied by adjusting the projecting length of stop 33. Suitable means, such as pin 34 on arm 18, is provided to limit the rotation of lever 22, shaft 19, and fingers 17.

As supporting arm 18 subsequently is pulled upwardly, the fingers 17 remain open with lever 22 ahead (to the right) of the longitudinal center line of arm 18, as shown in the uppermost of the alternate positions of arm 18 in Fig. 1. As arm 18 approaches the upward terminus, a second adjustable stop 35 is contacted by lever 22, again pushing lever 22 across the longitudinal center line of supporting arm 18 and closing fingers 17 with a snap about a folded bag 36 which had been positioned within the path of the fingers as hereinafter explained.

Bag separation

The mechanism for lifting a bag from a suitable stack and holding it in proper position to be grasped by fingers 17 as they are closed at the upward terminus includes an arm 38 pivotally mounted by shaft 39 and having a vacuum cup 40 at the outer end thereof (see Fig. 3). Through the rotation of shaft 39 the vacuum cup is raised and lowered from the supply of bags in a magazine 41. Shaft 39 is rotated and maintained in proper synchronization with the movement of supporting arm 18 by means of a chain 43 interconnecting sprocket 44 on shaft 39 and sprocket 45 on shaft 21. Through this interconnection, the vacuum cup 40 is timed to align bag 36 within the approaching open fingers 17 as arm 18 moves towards an upward position, and after supporting arm 18 moves downwardly, the vacuum cup 40 is brought into contact with the upper bag in magazine 41 to obtain a new bag to be gripped by fingers 17 and moved to the opening arm mechanism 16.

Vacuum cup 40 is connected to a suitable vacuum source by means of a flexible pipe or hose 46. A cam-actuated valve 47 is interposed in line 46 between the vacuum source and cup 40. Valve 47 is operated by means of a cam 48 on shaft 28 and is timed by the position of the cam 48 so that the vacuum of the cup will be broken as supporting arm 18 reaches its upper terminus and fingers 17 are closed over bag 36. The vacuum remains cut off until the supporting arm 18 has proceeded downwardly a sufficient distance for bag 36 to clear vacuum cup 40, after which time the vacuum to the cup is again restored so that as the cup is brought into contact

with the upper bag in magazine 41 a pickup will be made.

To assist the vacuum cup 40 in picking up a single bag from the top of the stack in magazine 41, an air jet 51 is provided to which air is supplied through pipe 52; the air being released from jet 51 along the edge of the bags in magazine 41 acts to ruffle the bags, to assist in separating the individual bags and to insure that the vacuum cup acquires a bag for loading. If desired, appropriate means may be installed to cause the air to be released from jet 51 in timed relationship with the movement of lifting arm 38.

Bag opening head

The action of the bag opening arm mechanism 16 is initiated by the approach of supporting arm 18 to its lower position. As the supporting arm 18 approaches the lower position a pair of bag opening arms 59 and 62 of arm mechanism 16 initially are closed as illustrated in solid lines in Figs. 1 and 2, and present a chisel or wedge shaped point 54 aligned with the line of movement of the bag 36. The necessity for such alignment will be readily apparent inasmuch as the object is to slip the closed bag over the point of the opening arm mechanism 16. The alignment is not too critical because of the action of the air blast in opening of the mouth of the bag.

As the bag 36 held by fingers 17 approaches the opening arm mechanism 16, a jet of air is projected upwardly from the ends of individual arms 59 and 62 of opening arm mechanism 16. This air jet is released through ports 66 and 67 in arms 59 and 62, respectively, and passes up along the plane of intersection of the two individual arms 59 and 62.

The timing of the air release is achieved through the use of a valve 68 actuated by a cam 69 on a shaft 28. From valve 68 a first pipe 70 leads to a source of air pressure, and a flexible pipe or hose 71 connects from timing valve 68 through a control valve 72 to suitable connections with the axial bores in arms 59 and 62 to transmit the air to ports 66 and 67. Valve 72 permits control of the quantity of air to be released from ports 66 and 67.

As has previously been explained, the bag 36 is tightly gripped by pins 26 with finger tips 21 being spaced a slight distance apart and serving primarily as guides. The upwardly projecting air blast from opening arm mechanism 16 enters the open end of the bag which at this time is pointed in a downward direction. The air is trapped in the front of the bag because of the grip maintained by pins 26 and causes extreme turbulence in the portion of the bag forwardly of those pins. This turbulence spreads the mouth of the bag so that the mouth of the bag slips easily over opening arm mechanism 16, even though the end of the arm mechanism 16 does not come to a sharp point.

After supporting arm 18 has proceeded sufficiently far downwardly for the fingers to slide the unsealed front of the bag well over the chisel point 54 of the mechanism 16, a bumper 55 on arm 18 contacts actuating lever 56 affixed to shaft 57 to open the arm mechanism 16.

A gear segment 58 and an individual arm 59 are also affixed to shaft 57 which is journaled for rotation in the sub-frame 60. The other individual arm 62 of arm mechanism 16 is affixed to shaft 63, the latter being also journaled in sub-frame 60. A second gear segment 64 is attached to shaft 63 and meshes with gear segment 58 on

shaft 57. As actuating lever 56 is pushed downwardly by bumper 55, shaft 57 is rotated in a clockwise direction and shaft 63 is rotated in a counter-clockwise direction to spread individual arms 59 and 62. The timing of the movement of arm mechanism 16 may be adjusted by varying the projecting length of bumper 55. As has previously been explained, stop 33 acts at substantially the same time to open finger mechanism 15.

As actuating lever 56 is moved downwardly by bumper 55 it is latched by a catch 74 held over lever 56 by the action of spring 75 and connecting rod 76. As arm 18 starts back upwardly the bag which has been opened by arm mechanism 16 is held open and securely in place as is shown in dotted lines in Fig. 2. When opened the individual arms 59 and 62 allow sufficient space between their inner faces for convenient insertion of the material to be placed in the bag. If the whole of the bag has not been fully opened by the action of the opening arm mechanism 16 in opening the mouth of the bag, the remainder of the bag may be pushed open by the insertion of the desired filling material into the bag. Suitable grippers are provided to hold the bag in place so that the action of the filling material entering the bag will not pull the bag loose from opening arm mechanism 16.

Resiliently actuated grippers 78 and 79 cooperate with arms 59 and 62 respectively to hold the bag securely in place as it is being filled. Grippers 78 and 79 are pivotally mounted on shafts 57 and 63 respectively. As shown in Fig. 2, a rod 86 attached to opening arm 62 by bolt 87 extends freely through an opening in the lower end of gripper 78. A compression spring 88 is abutted against the face of gripper 78 at one end and stop nuts 89 at the other end. Stop nuts 91 on rod 86 butt against the outer face of the lower end of gripper 78.

As the lower end of opening arm 62 moves to the right, rod 86 through stop nuts 89 and spring 88 pivots gripper 78 counterclockwise to take hold of the bag. A similar mechanism about rod 92 operates gripper 79 in response to movements of opening arm 59.

The opened bag held by arm mechanism 16 may be filled during the period of time that supporting arm 18 is rotating upwardly. As the arm 18 approaches an upward position the forward edge of the arm contacts a pin 90 on lever 81 causing that lever to rotate about a suitable mounting pin 92. The rotation of lever 81 results in a similar rotation of catch 74, through the interconnection provided by connecting rod 76, and releases actuating lever 56 to allow tension spring 84, between the lower end of individual arm 59 and sub-frame 60, to rotate arms 59 and 62 toward the closed position. The closing of the bag opening arm mechanism 16 releases the filled bag which then may be removed either by hand or by suitable machinery.

Figure 5 illustrates a second embodiment in which the bag 36A is opened and held in a horizontal position for filling. The only substantial difference in the operation of the embodiment of Figure 5 and that of Figure 1 is that supporting arm 18A of Figure 5 moves a relatively short distance as compared to the movement of supporting arm 18 of Figure 1. As a result, the movement of supporting arm 18A must be somewhat slower as compared to the movements of the co-operating parts, such as lifting arm 38A and opening arm mechanism 16A.

Figure 6 illustrates the manner in which the

present invention may be adapted to open and hold bags for filling in a vertical position with the mouth of the bag upwardly. The operation of the various parts, such as supporting arm 18B, finger mechanism 15B, opening arm mechanism 16B, and lifting arm mechanism 38B is substantially identical to that of the corresponding parts of Figure 1 and additional description is believed to be unnecessary.

10 The description of specific embodiments of the invention is made to comply with the provisions of Section 4883 of the Revised Statutes and, because it will call attention to a number of additional uses and embodiments of the invention, it 15 should not be construed as applying any unnecessary limitations to the appended claims. For example, the "bag" might be a tube-like element, sealed at one end, and yet certain of the teachings of the invention might be applicable 20 thereto.

I claim:

1. In a device of the class described, a pair of fingers, means to move said fingers along a pre-determined path from a first to a second point, 25 means adjacent the first point to insert a bag between the fingers with the one end thereof directed along said path towards said second point and to close said fingers against said bag, each of said fingers including a finger tip, means to the rear of said finger tips to tightly grip the bag and to prevent air entering the mouth of said bag from passing to the rear of the bag, said finger tips and said last mentioned means being so positioned with respect to each other that the finger tips will be spaced apart when said fingers are 30 closed over a bag, and means at said second point to open said bag and hold it in position for filling including a pair of arms fitting together to form an opener intersecting said path to penetrate the 35 open end of the bag as the latter is moved to said second point by said fingers, a port through which the air may be released to enter the mouth of said bag as it approaches said opener whereby said air will be trapped within the mouth of said bag thereby spreading the mouth to allow the bag 40 to slip over the opener, and means to separate 45 said arms to open the mouth of said bag.

2. A method of opening a folded paper bag, or the like, said method including the steps of applying pressure to each side of the bag substantially across the width thereof a fraction of the 50 length of the bag below the mouth thereof, said pressures each being toward the other to provide a seal across the bag, directing a jet of air at the mouth of the bag to spread the lips of the bag, 55 inserting a pair of arms within the spread lips and moving the arms outwardly to further open the mouth of the bag, releasing said pressure, and continuing to move said arms outwardly to complete the opening of the bag.

60 3. A bag-opening device, including a frame, a carrier movably mounted on said frame, a pair of fingers pivotally mounted on said carrier for movement by the carrier from a first to a second point, means interconnecting said fingers for movement in unison, a pivoted lever on said carrier and operatively connected to said means and fingers, said lever being pivotable from a first position wherein said fingers are closed to a second position wherein said fingers are open, spring means connected to said lever urging said lever into either said first or said second position from an intermediate position, a bumper attached to said frame and adjacent said first point to contact said lever and to pivot it from

75

the second to the first position, a second bumper attached to said frame and adjacent said second point to contact said lever and to pivot it from the first to the second position, power-driven means to move said carrier and fingers from said first to said second point, and return, and to bring said lever into contact with said bumpers whereby said fingers will be closed as they move from said first to said second point and open as they move from said second to said first point, means adjacent the first point to insert a bag between the fingers with the open end of the bag directed along the path of movement of the fingers toward the second point, and means adjacent said second point to enter the open end of the bag and to open the bag.

4. A bag-opening device, including a frame, a carrier movably mounted on said frame, a pair of fingers pivotally mounted on said carrier for movement by the carrier from a first to a second point, means interconnecting said fingers for movement in unison, a pivoted lever on said carrier and operatively connected to said means and fingers, said lever being pivotable from a first position wherein said fingers are closed to a second position wherein said fingers are open, spring means connected to said lever urging said lever into either said first or said second position from an intermediate position, a bumper attached to said frame and adjacent said first point to contact said lever and to pivot it from the second to the first position, a second bumper attached to said frame and adjacent said second point to contact said lever and to pivot it from the first to the second position, power-driven means to move said carrier and fingers from said first to said second point, and return, and to bring said lever into contact with said bumpers whereby said fingers will be closed as they move from said first to said second point and open as they move from said second to said first point, means adjacent the first point to insert a bag between the fingers with the open end of the bag directed along the path of movement of the fingers toward the second point, a pair of arms pivotally attached to said frame with the ends of said arms fitting together to form a chisel-pointed opener when in a closed position, means interconnecting said arms for movement in unison to an open position whereat said ends have spread apart, a pivoted lever operatively connected to said last mentioned means and arms, resilient means urging said arms toward said closed position, and a bumper on said carrier and positioned to contact said last mentioned lever as said fingers move to said second point to pivot said lever and to move said arms from said closed to said open position.

5. A bag-opening device including a frame, a carrier movably mounted on said frame, a pair of fingers on said carrier for movement by the carrier from a first to a second point, means adjacent the first point to insert a bag between the fingers and to close the fingers against the sides of the bag, means to move the carrier with the open end of said bag forward towards said second point, and return, means adjacent said second point to release said fingers from said bag, a pair of arms pivotally attached to said frame with the ends of said arms fitting together to form a chisel-pointed opener when in a closed position, means interconnecting said arms for movement in unison to an open position whereat said ends have spread apart, a pivoted lever operatively connected to said last mentioned

means and arms, resilient means urging said arms toward said closed position, and a bumper on said carrier positioned to contact said lever as said fingers move to said second point to pivot said lever and to move said arms from said closed to said open position.

6. A bag-opening device including a frame, a carrier movably mounted on said frame, a pair of fingers on said carrier for movement by the carrier from a first to a second point, means adjacent the first point to insert a bag between the fingers and to close the fingers against the sides of the bag, means to move the carrier with the open end of said bag forward towards said second point, and return, means adjacent said second point to release said fingers from said bag, a pair of arms pivotally attached to said frame with the ends of said arms fitting together to form a chisel-pointed opener when in a closed position, means interconnecting said arms for movement in unison to open position whereat said ends have spread apart, a pivoted lever operatively connected to said last mentioned means and arms, resilient means urging said arms toward said closed position, a bumper on said carrier positioned to contact said lever as said fingers move to said second point to pivot said lever and to move said arms from said closed to said open position, a latch to hold said arms in said open position, and means to release said latch as said carrier moves said fingers to said first point.

7. In a device of the class described, a frame, a carrier movably mounted on said frame, a pair of fingers mounted on said carrier with the tips of the fingers movable toward and away from each other to permit bags to be inserted therebetween and the fingers to be closed against the sides of the bags, power means connected to said carrier to move the fingers on the carrier along a predetermined path from a first to a second point, means adjacent the first point to insert a bag between the fingers with the open end of the bags forward toward said second point and to close the fingers against the sides of the bag, pointed means attached to said frame and positioned with the point thereof in said path between said first and second points and directed toward said first point whereby as said fingers move toward said second point with the bag therebetween the open end of the bag will be slipped over said pointed means, said pointed means including two separable portions and means to move said portions apart after said bag has been slipped over said point, and means adjacent said second point to release said bag from said finger tips after the bag has been slipped over said pointed means.

8. In a device of the class described, a frame, a carrier movably mounted on said frame, a pair of fingers mounted on said carrier with the tips of the fingers movable toward and away from each other to permit bags to be inserted between the fingers and the fingers to be closed against the sides of the bags, power means connected to said carrier to move the fingers on the carrier along a predetermined path from a first to a second point, means adjacent the first point to insert a bag between the fingers with the open end of the bag forward toward said second point and to close the fingers against the sides of the bag, a pair of arms the ends of which fit together to form a chisel-pointed opener, said arms being movably mounted so that said ends thereof may be spread apart, said arms being positioned on

said frame with the chisel point thereof in said path between said first and second points and directed toward said first point whereby as said fingers move toward said second point with a bag therebetween the open end of the bag will be slipped over said point, means to move said arms apart after the bag has been slipped thereover whereby the sides of the bag will be spread apart by the movement of the arms, and means adjacent said second point to move said finger tips apart to release the bag after the bag has been slipped over said pointed means.

9. In a device of the class described, a frame, an arm pivotally mounted on said frame, a pair of fingers mounted on said arm with the tips of the fingers movable toward and away from each other to permit bags to be inserted therebetween and the fingers to be closed against the sides of the bags, power means connected to said arm to pivot the arm to move the fingers along a predetermined path from a first to a second point, means adjacent the first point to insert a bag therebetween the fingers with the open end of the bag forward toward said second point and to close the fingers against the sides of the bag, a pair of arms movably mounted on said frame, the ends of said pair of arms fitting together to form a chisel-pointed opener, said ends being movable away from each other, said pair of arms being positioned on said frame with said chisel point thereof in said path between said first and second points and directed toward said first point whereby as said fingers move toward said second point with the bag therebetween the open end of the bag will be slipped over said chisel point, said arms having ports directed to release fluid therefrom along said path toward said first point whereby fluid from said ports will spread the mouth of the approaching bag, means to move said ends of said arms apart after said bag has been slipped over said arms, and means adjacent said second point to move said finger tips apart to release the bag after the bag has been slipped over said arms.

10. In a device of the class described, a frame, an arm pivotally mounted on said frame, a pair of fingers mounted on said arm with the tips of the fingers movable toward and away from each other to permit bags to be inserted therebetween and the fingers to be closed against the sides of the bags, power means connected to said arm to pivot the arm to move the fingers along a predetermined path from a first to a second point, means adjacent the first point to insert a bag therebetween the fingers with the open end of the bag forward toward said second point and to close the fingers against the sides of the bag, a pair of arms movably mounted on said frame, the ends of said pair of arms fitting together to form a chisel-pointed opener, said ends being movable away from each other, said pair of arms being positioned on said frame with said chisel point thereof in said path between said first and second points and directed toward said first point whereby as said fingers move toward said second point with the bag therebetween the open end of the bag will be slipped over said chisel point, said arms having ports directed to release

fluid therefrom along said path toward said first point whereby fluid from said ports will spread the mouth of the approaching bag, means to move said ends of said arms apart after said bag has been slipped over said arms, means adjacent said second point to move said finger tips apart to release the bag after the bag has been slipped over said arms, and means to bring said pair of arms together to release said open bag subsequent to the release of said fingers from said bag.

11. In a device of the class described, a frame, a carrier movably mounted on said frame, a pair of fingers mounted on said carrier with the tips of the fingers movable toward and away from each other to permit bags to be inserted between the fingers and the fingers to be closed against the sides of the bags, power means connected to said carrier to move the fingers on the carrier along a predetermined path from a first to a second point, means adjacent the first point to insert a bag between the fingers and to close the fingers against the sides of the bag, a pair of arms the ends of which fit together to form a chisel-pointed opener, said arms being movably mounted so that said ends thereof may be spread apart, said arms being positioned on said frame with the chisel point thereof in said path between said first and second points and directed toward said first point whereby as said fingers move toward said second point with a bag therebetween the open end of the bag will be slipped over said pointed means, means to move said arms apart after the bag has been slipped thereover whereby the sides of the bag will be spread apart by the movement of the arms, means adjacent said second point to move said finger tips apart to release the bag after the bag has been slipped over said pointed means, and a pair of grippers attached to said frame and positioned to cooperate with said arms to hold a bag for filling after the bag has been opened by the arms.

12. A method of preparing a folded paper bag, or the like, for filling, said method including the steps of applying pressure to each side of the bag substantially across the width thereof a fraction of the length of the bag below the mouth thereof, said pressures each being toward the other to provide a seal across the bag, directing a jet of air at the mouth of the bag to spread the lips of the bag, inserting a pair of arms within the spread lips and moving the arms outwardly to further open the mouth of the bag, releasing said pressure, continuing to move said arms outwardly to complete the opening of the bag, and grasping the walls of the bag adjacent the mouth thereof to hold the bag in position for filling.

HARVEY A. EDMONDS.
